RESISTANCE APPARATUS

Clarence R. Dickinson, Greendale, and Bernhard F. Tellkamp, Muskego, Wis., assignors to Allen-Bradley Company, Milwaukee, Wis., a corporation of Wisconsin

Application October 14, 1953, Serial No. 385,952

8 Claims. (Cl. 201—48)

This invention relates to variable resistance apparatus such as is commonly employed for rheostats and potentiometers and resides more specifically in variable resistance apparatus that may be compacted to within small overall dimensions for use in circuits having a great number of components confined within small space limits, or in other instances where compactness or light weight are of dominating concern.

The invention relates primarily to so-called integrally molded variable resistance apparatus in which there is provided a molded base of insulating material having a layer of dispersed conducting particles that form a resistance track integrally embedded therein and a similar layer of more densely distributed conducting particles that form a collector track of negligible resistance also embedded therein, the tracks each being insulated from one another and exposed to one side of the base with concentrically arranged contact surfaces. The contact surfaces are electrically bridged by a rotatably mounted brush of conducting material having a set of contact faces held in bearing engagement with the exposed track surfaces. Ends of terminal leads are embedded in the base in electrical contact with the tracks and extend therefrom for suitable connection with other circuit components or conductors. Molded apparatus, as here described, has highly desirable operating and life characteristics and this invention increases the range of application of such apparatus.

It is an object of this invention to provide a variable resistance apparatus as described with high leakage resistance between the conducting portions of the apparatus and grounded metallic portions to permit a compacting to within small overall dimensions. Upon compacting, leakage resistance paths become foreshortened and maximum voltage ratings will be decreased accordingly. In the practice of this invention, however, there may be employed a novel arrangement of insulating material that jackets the conducting circuit elements in manner to retain leakage resistance at high values heretofore had with larger apparatus.

It is another object of this invention to provide a variable resistance apparatus with terminal leads mounted to withstand substantial abusive handling of the outer ends to which connections are made without dislocation of the embedded ends in electrical contact with the resistance and collector tracks.

It is another object of this invention to provide a variable resistance apparatus with a sliding brush in contacting relation with resistance and collector tracks that has a substantially constant contact pressure between brush and tracks throughout the full range of brush movement and over an extended period of use.

It is still another object of this invention to provide

2

a variable resistance apparatus as described that may be compacted within small overall dimensions without undesirable decrease in power rating heretofore had in larger apparatus. To retain wattage ratings comparable

5 with that of larger apparatus, while permitting reduction in overall dimensions, a heat conducting element is embedded within the molded insulating base of which the resistance track is a part. This element extends to within close proximity of the resistance track to provide
10 a conductive path for the heat generated within the track and extends to the exterior of the base to a heat conductive connection with portions of a metallic covering to readily dissipate the heat conducted away from the resistance track.

15 These and other objects and advantages of this invention will appear in the description to follow. In the description reference is made to the accompanying drawings in which there is shown by way of illustration and not of limitation a specific form in which the invention may be embodied.

In the drawings:

Fig. 1 is a side view in elevation and in section of a variable resistance apparatus in which this invention is embodied,

25 Fig. 2 is a rear view in elevation and in section of the apparatus viewed through the plane 2—2 indicated in Fig. 1,

Fig. 3 is a front view in elevation and in section of the apparatus viewed through the plane 3—3 indicated
30 in Fig. 1,

Fig. 4 is a top plan view of the apparatus shown in Fig. 1,

Fig. 5 is a view in perspective of a subassembly that forms a portion of the apparatus,

35 Fig. 6 is a view in perspective of a brush carrier and operating shaft forming a part of the apparatus,

Fig. 7 is a front view in elevation of the brush carrier and operating shaft assembly shown in Fig. 6,

40 Fig. 8 is a fragmentary side view in elevation with parts broken away and in section of the brush carrier and operating shaft assembly viewed through the plane 8—8 indicated in Fig. 7,

Fig. 9 is a view in perspective of a heat conducting insert that forms a part of the apparatus and which is
45 embedded within the molded base, and

Fig. 10 is a view in perspective of an electrically conducting brush that forms a part of the apparatus.

In the embodiment of this invention shown in the drawings, which is a variable resistance apparatus suitable for use as a potentiometer or rheostat, there is provided a base 1 of molded insulating material having a circular track 2 of conducting resistance material and a circular collector track 3 likewise of conducting material, each track being integrally molded with the base

55 1 to form a unitary whole. The base 1 is preferably formed of a molded synthetic resin having desirable insulating qualities that electrically separates the track 2 from the track 3. The resistance track 2 comprises a shallow layer exposed on the rear face of the base 1 of finely divided conducting particles of carbon black distributed to obtain desired resistance characteristics.

Similarly, the conducting track 3 is composed of a shallow layer exposed at the rear of the base 1 of conducting carbon black particles that are more densely distributed than in the track 2 to provide a conducting path having a negligible resistance. Apparatus employing conducting particles molded within an insulating base are termed

integral molded resistor units and have been described and disclosed in detail in Patents No. 2,269,136 issued to Bernhard F. Tellkamp on January 6, 1942 and No. 2,514,682 issued to Bernhard F. Tellkamp on July 11, 1950.

Embedded within the base 1, at the time of molding, is a set of three terminal leads comprising a center lead 4 with an embedded end extending to within the collector track 3, as shown in Fig. 1, to form an electrical connection, and a pair of outer leads 5 disposed to each side of the center lead 4 with embedded ends in electrically conducting relation with the ends of the resistance track 2. The embedded ends of the leads 4, 5 are in intimate contact with the resin forming the base 1 and are of a configuration to be securely anchored to resist being pulled or twisted out of position, unless an excessive abusive force be applied. From the embedded ends each lead 4, 5 emerges into a central shank portion 6 and hence into a free end 7 suitable for connection with conductors extending to other circuit elements. Connection may readily be made by soldering and the leads 4, 5 are formed of a conductive material such as plated copper wire that is highly bendable, to enhance the ease with which such connections may be made.

Also embedded within the base 1 at the time of molding is a heat extracting element 8 of high heat conductivity formed as shown in Fig. 9. The element 8 is curved to present an after edge 9 that describes a partial circle which is disposed in close proximity to the resistance track 2, as shown in Fig. 1. The element 8 provides a path to conduct heat generated within the resistance track 2 away from the interior of the base 1, but is spaced sufficiently far from the track 2 to maintain a desired high value leakage resistance to retain a high breakdown voltage rating.

The front margin of the element 8 is provided with a plurality of ears 10, as shown in Fig. 9, which are inserted through mating openings 11 in a front plate 12, after molding is completed, and then bent over to clinch the base 1 and plate 12 together. The plate 12 has a dished central area in which the ears 10 are received and the contacting engagement between the ears 10 and plate 12 forms a heat conducting path to lead heat away from the element 8.

Clampingly held between the front face of the base 1 and the front plate 12 is a molded insulating shell 13 with a central opening in which the dished portion of the cover plate 12 is seated. The shell 13 turns about the cylindrical side of the base 1 to extend rearwardly in the form of a rim 14, as is clearly shown in Figs. 1, 2 and 5. The rim 14 is spaced from the base 1 and extends to the rear of the face of the base 1 upon which the tracks 2 and 3 are exposed. As is more clearly shown in Fig. 5, the rim 14 does not fully encircle the base 1 and at the upper portion of the shell 13, where the rim 14 is discontinued, there rises a supporting insulating wall 15 adjacent the shank portions 6 of the leads 4, 5. The wall 15 is an integral part of the shell 13 and forms an insulating barrier between the leads 4, 5 and the front plate 12.

Riveted to the front plate 12 is a bushing 16 threaded to receive suitable mounting hardware, not shown. Extending through the bushing 16 is an operating shaft 17 with an inner end 18 of reduced diameter and disposed on the inner end 18 is a molded brush carrier 19. The carrier 19 has a circular front face 20 of a diameter substantially the same as that of the rear face of the base 1, so that upon inserting the shaft 17 through the bushing 16 the brush carrier 19 may be brought up in facing relation to the base 1 to cover the tracks 2 and 3. In this position the carrier 19 fits within the rim 14 of the insulating shield 13 that extends rearwardly of the base 1, as shown in Fig. 1. A collar 41, forming a part of the carrier 19, encircles the shaft 17 and extends to the front of the face 20 to be received within the central

opening of the base 1 and to electrically shield the collector track 3 from the shaft 17.

Held by riveted engagement to the after end of the shaft 17 is a disc 21 with a forwardly turned ear 22 extending within a recess 23 in the brush carrier 19. Rotation of the shaft 17 will then cause the brush carrier 19 to be rotated in like direction. The disc 21 is formed with a radially extending lug portion 24 that lays upon a portion of the carrier 19 having a like configuration. The lug 24 cooperates with a stop, to be described that limits the rotation of the shaft 17.

As shown in Figs. 7 and 8 the brush carrier 19 is recessed to house a conducting brush 25 and a staple shaped contact pressure spring 26. The spring 26 has a central portion 42 positioned to bear against the curved back of the brush 25 and a pair of leg portions 43 that each terminate in a turned end 27 received within a socket 28 in the carrier 19. The two leg portions 43 extend over abutments 29 that project from the floor of the recess within the carrier 19 and upon insertion of the brush 25 within the recess the spring 26 is bent about the abutments 29 into the dotted position of Fig. 8. The abutments 29 provide a fulcrum about which the spring 26 may be turned and the leg ends 27 bear against the socket walls for a reaction to the bending distortion of the spring 26 caused by the insertion of the brush 25.

As shown in Fig. 10, the brush 25 has a single foot 30 at one end for engagement with the resistance track 2, and a pair of collector feet 31 at the opposite end for engagement with the collector track 3. A conductive carbon material is employed for the brush 25 to provide a low resistance conductor for bridging the tracks 2 and 3. The carbon material composing the brush must not rub off upon the tracks 2 and 3 to form a superimposed conducting layer and it must not scratch or otherwise mar the track surfaces. Such a brush has been described in greater detail in the patent to Tellkamp, No. 2,514,682. With the brush 25 and spring 26 inserted within the carrier 19 and the shaft 17 passed through the bushing 16 to bring the carrier 19 into close facing relation with the tracks 2 and 3 a retaining ring 32, that bears against a washer 33 at the front of the bushing 16, is placed in the mating groove in the shaft 17 to retain the elements in assembly. With the elements in assembly the brush 25 is retained within the carrier recess to distort the spring 26, which in turn acts upon the brush to provide desired bearing pressure between the brush feet 30, 31 and the tracks 2, 3.

A cylindrical metallic cover 34, closed at the rear and open at the front houses the base 1 and carrier 19. A set of ears 35 extending from the front edge of the cover 34 are turned over the front plate 12 to secure the cover 34 in position. A portion of the cover 34 at the top and front is notched to receive a molded terminal guide 36 of insulating material that extends from within the cover 34 to the exterior. The terminal guide 36 has a circular groove 44 formed in the rear face to seat upon a lip 37 defining the notch in the cover 34. The groove 44 forms a ridge 38 that extends along the inner side of the cover 34 as an extension of the rim 14 of the insulating shield 13. As shown in Figs. 1 and 2, the rim 14 and the ridge 38 together form a circular insulating shield fully surrounding the gap between the base 1 and the brush holder 19. This shield, spaced both from the metallic cover 34 and the base 1 provides a high resistance leakage path between the conducting resistance track 2 and the cover 34, which will normally be at near ground potential. As clearly shown in Figs. 1-4, the terminal guide 36 is adjacent to and fits in mating relation with the supporting wall 15 of the shell 13. The guide 36 and wall 15 snugly surround a substantial length of the shank portions 6 of the terminal leads 4, 5 that emerge from the base 2, and are disposed to support the leads 4, 5 as reaction mem-

bers upon side thrusts being applied to the free ends of the leads 4, 5.

Riveted to the cover 34 in a position to obstruct the lug portion 24 of the disc 21 is a stop 39. The stop 39 limits the rotation of the shaft 17 and the brush 25 to prohibit the contacting foot 30 on the brush 25 from riding beyond the limits of the resistance track 2, which is in the form of a partially complete circle. For mounting the apparatus on a panel board, or the like, a pair of fingers 40 are provided on the cover 34 that extend forwardly, as shown, to be adaptable for insertion in openings provided in the panel upon which the apparatus is to be mounted. The apparatus will then be orientated in position and will be restrained from twisting upon rotation of the operating shaft 17.

The form of the apparatus of this invention is well adapted for compacting into a small unit to provide a variable resistance unit particularly useful in aircraft and other applications where space and weight are premium factors. Upon compacting, the dissipation of the heat arising in the resistance track must be rapid if it is desired to retain wattage ratings formerly had in larger devices. To enhance the rate of dissipation in the apparatus of this invention the heat extractor 8 connects with the external metal portions of the apparatus comprising the front plate 12 and cover 34. Heat generated within the molded base 1 is then quickly conducted to the cover and the mounting panel which present large radiating surface areas for rapid heat dissipation.

To facilitate the compacting, bendable leads of small cross section are employed that may be turned and bent to suit the party making the electrical connections with conductors and other circuit components. To support the leads in fashion to resist excessive lateral stress and isolate the embedded roots of the leads in the base 1 from such stress the shanks 6 of the leads are snugly surrounded by supporting insulation. The insulation, in the form of the wall 15 and the terminal guide 36, extends along a substantial length of each lead shank 6 to provide extended reaction areas against which the leads may bear in reaction to lateral stresses being applied thereto. The embedded roots will not be subjected to these lateral stresses and the possibility of fault appearing in the base 1 or between the base 1 and a lead 4, 5 is precluded.

As has been noted herein, compacting of a variable resistance through the employment of this invention may be further enhanced by reason of the jacketing of the conducting elements within an insulation shield. The leads 4, 5 are surrounded by insulating members to retain high leakage resistance paths with the normally grounded protective front plate 12 and the cover 34. The resistance and collector tracks 2, 3 are insulated to the front by the base 1 and are jacketed to the rear by the brush holder 19 and to the peripheral sides by the rim 14 and ridge 38. To provide a high leakage resistance path between the operating shaft 17 and the inner edge of the collector track 3 the carrier 19 is extended within the central opening of the base 1 in the form of the collar 41. This protective jacketing, which in turn is encapsulated in a sturdy metallic cover, permits both compacting and usage where severe handling may be encountered.

For reliable operation, resistance values for particular brush positions should be maintained consistent over an extended period of use. Consistency depends largely upon brush pressure determined by the spring 26. To maintain substantially constant spring pressure a spring with a flat spring rate characteristic within the range of deflection encountered should be employed. In this invention the spring is formed to present an extended active length comprising a central section that engages the brush and legs extending at angles thereto. This form permits compacting of the apparatus without forfeiture of beneficial spring length. The spring is held in fixed position by engagement of the toes 27 within the sockets 28 and by the spring legs being pressed against the

abutments 29. There is thus provided a variable resistance having characteristics including long life and uniformity of resistance values over a period of use wherein high leakage resistance and power ratings need not be sacrificed with compacting of the apparatus.

We claim:

1. In a variable resistance apparatus the combination comprising a molded base of insulating material having an exposed circular resistance track at the rear formed of conducting particles molded integrally within the material comprising said base and having side facing extending forwardly to the front, a brush carrier to the rear of said resistance track rotatably mounted for movement about an axis substantially concentric with said resistance track, a brush held in sliding engagement with said resistance track by said carrier and rotatable therewith, a bendable terminal lead having one end embedded at the time of molding within said molded base in electrical contact with said resistance track and having a shank portion emerging and extending outwardly from the side facing of said base terminating in a free end suitable for electrical connection with circuit components and leads, an insulating shell having a front wall and a rim extending rearwardly from the wall with a gap in the rim and a radial extension of the front wall at the gap, which shell receives the base with the front wall thereof immediately to the front of the base and the rim extending along the side facing of the base with the gap therein receiving the terminal lead which is disposed adjacent the radial extension of the front wall, a rim continuation of insulating material closing the gap in said rim and having a portion alongside said terminal lead that supplements said radial extension of the front wall whereby said radial extension and rim continuation form a terminal lead supporting means of insulating material closely surrounding the shank of said lead for a substantial distance beyond the point of emergence of said lead to isolate the embedded end from bending forces applied to the free end of the lead, and mounting means retaining said molded base said insulating shell and said rim continuation in fixed relation.
2. In a variable resistance apparatus the combination comprising a molded base of insulating material having cylindrical side facing and a rear face exposing a circular collector track and a circular resistance track spaced from and substantially concentric with said collector track each formed of conducting particles molded integrally within said base, a brush carrier to the rear of said resistance and collector tracks rotatably mounted for movement about an axis substantially concentric with said tracks, a brush held in bridging contact with said tracks by said brush carrier and rotatable therewith, a set of bendable terminal leads having an end of each embedded at the time of molding within said molded base in electrical contact with one of said concentric tracks and having shank portions emerging and extending outwardly from the side facing of said base that terminate in free ends suitable for electrical connection with circuit component and leads, an insulating shell having a front wall and a rim extending rearwardly from the front wall with a gap in the rim and a radial extension of the front wall at the gap, which shell receives the base with the front wall thereof immediately to the front of the base and the rim extending about the side facing of the base with the gap therein receiving the terminal leads which are disposed adjacent the radial extension of the front wall, a rim continuation of insulating material closing the gap in said rim and having a portion alongside said terminal leads that supplements said radial extension of the front wall whereby said radial extension and rim continuation form a terminal lead supporting means of insulating material closely surrounding the shank of each lead for a substantial distance beyond the point of emergence of each to isolate the embedded ends of the leads from bending forces, applied to the free ends thereof, and

mounting means retaining said molded base, said insulating shell and said rim continuation in fixed relation.

3. In a variable resistance apparatus the combination comprising a molded base of insulating material having a circular collector track and a circular resistance track spaced from and substantially concentric with said collector track each formed of conducting particles molded integrally within said base, a brush carrier rotatably mounted for movement about an axis substantially concentric with said tracks having a pair of abutments adapted to be spring fulcrums, a brush held by and rotatable with said brush carrier in bridging contact with said tracks, a spring interposed between said brush and said carrier having a straight center section bearing against the side of said brush opposite said tracks and a pair of leg sections forming integral extensions of said center section extending at an angle thereto in a direction substantially normal to the thrust delivered to said brush with the extended ends thereof pivotally joined to said carrier and having an intermediate portion of each leg bearing against one of said carrier abutments on the side of said spring opposite that engaging said brush, a set of bendable terminal leads having an end of each embedded at the time of molding within said molded base in electrical contact with one of said concentric tracks and having shank portions emerging and extending outwardly from said base that terminate in free ends suitable for electrical connection with circuit components and leads, and terminal lead supporting means of insulating material closely surrounding the shank of each lead for a substantial distance beyond the point of emergence of each to isolate the embedded ends of the leads from bending forces applied to the free ends thereof.

4. In a variable resistance apparatus the combination comprising a base of insulating material; a circular track of resistance material supported by said base having an exposed contact face; a collector track of conducting material supported by said base spaced from said resistance track and having an exposed contact face substantially concentric with said resistance track; a rotatable brush carrier in facing relation to the exposed contact faces of said tracks having a pair of spaced spring receiving sockets therein and having a pair of abutments projecting toward said base adapted to act as spring fulcrums, each fulcrum being adjacent one of said sockets and disposed on the same side of a line extending between the sockets; a conducting brush held by and rotatable with said brush carrier having contact projections resting in sliding engagement with said resistance and collector tracks to electrically bridge the same, and having a back face disposed away from said base; and an elongated staple shaped spring interposed between said brush and said brush carrier with a central section bearing against the back of said brush to urge the same into contacting engagement with said tracks, and with a pair of elongated leg sections extending from said center section on opposite sides of the axis of rotation with the ends thereof secured by said sockets and the intermediate portions of the spring legs in bearing engagement with and fulcrumed on said abutments to exert resilient pressure on said brush in the direction of said base.

5. In a variable resistance apparatus the combination comprising a molded base of insulating material with a rear portion of circular cross section terminating in a rear face upon which is exposed a circular resistance track and a circular collector track spaced from and substantially concentric with said resistance track, each track being formed of conducting particles integrally molded within said base; a heat extractor of relatively high heat conductivity formed of thin sheet material cylindrically curved to match the circular resistance track which is embedded within said base with the generatrix of the surface of the sheet being normal to the plane of said tracks and with an after edge in close proximity to said resistance track adapted to receive heat there-

from, said heat extractor having emerging portions to the front of said base; a front housing portion of relatively high heat conductivity engaged in heat conducting relation with said protruding portions of said heat extractor; an insulating shell held between said base and said front housing portion turning around the sides of said molding and extending in the form of a rim spaced from said base rearwardly of said rear face of said base; a brush carrier rotatably mounted for movement about an axis substantially concentric with said tracks mounted in facing relation with the rear face of said base with a face area substantially coextensive with said rear face and received within the rim of said insulating shell to enclose said collector and resistance tracks within an insulating jacket comprising said base to the front of the tracks, said rim to the peripheral outside of said tracks and said carrier to the rear of said tracks; a brush held in bridging contact with said tracks by said brush carrier and rotatable therewith; and an outer protective housing of heat conductive material enclosing said base, brush holder and rim and secured to said front housing portion in heat conductive relation thereto.

6. In a variable resistance apparatus the combination of a base of insulating material with a rear face presenting an arcuate resistance track, an arcuate metallic insert of thin sheet material embedded in said base with the surface of the material extending substantially normal to the rear face to present an edge in close proximity to said resistance track and projecting forwardly from said edge with a set of attachment ears protruding from the front of the base, an insulating shell having a front portion abutting the front of the base and turning rearwardly along side the base with a rim spaced outwardly from the base, a metallic front cover abutting said insulating shell with said attachment ears extending therethrough and clinched over the front cover to rigidly secure the cover, base and shell in assembly, a metallic shaft supporting member seated upon said front cover in heat conducting relation thereto, a carrier assembly including a shaft borne by said member that extends rearwardly through said base and a contact brush mounted on the shaft in contacting relation with the resistance track, and a cover joined to said front cover enclosing the base and shell with a gap between the cover and the rim of the shell.

7. In a variable resistance apparatus the combination comprising a molded base of insulating material having a circular collector track and a circular resistance track spaced from and substantially concentric with said collector track each formed of conducting particles molded integrally with said base, a brush carrier rotatably mounted for movement about an axis substantially concentric with said tracks having a pair of abutments adapted to be spring fulcrums, a brush held by and rotatable with said brush carrier in bridging contact with said tracks, a spring interposed between said brush and said carrier having a straight center section bearing against the side of said brush opposite said tracks and a pair of leg sections forming integral extensions of said center section extending at an angle thereto in a direction substantially normal to the thrust delivered to said brush with the extended ends thereof pivotally joined to said carrier and having an intermediate portion of each leg bearing against one of said carrier abutments on the side of said spring opposite that engaging said brush, and a set of terminal leads having an end of each embedded within said molded base in electrical contact with one of said concentric tracks and extending outwardly from said base to terminate in free ends suitable for electrical connection with circuit components and leads.

8. In a variable resistance apparatus the combination comprising a base of molded insulating material having an arcuate resistance track on one face thereof formed with conductive particles integrally molded within the base to form a unitary whole; an arcuate metallic heat

extracting insert comprising a thin sheet embedded within said base at the time of molding that is cylindrically formed with the generatrix of the cylindrical configuration being normal to the plane of the resistance track and the generatrix following an arcuate path substantially like that of the resistance track, said metallic insert having an edge that is within the base in close proximity to the resistance track from which edge it extends to the side of the base opposite the track to emerge therefrom with a set of attachment ears; and a metallic heat con-

ductive member secured to the heat extracting insert by clinching the attachment ears over the member.
